MAINTENANCE VEHICLE LADDER RACK

Hiroshi Kira, 8227 Remmet,
Canoga Park, Calif. 91304

Filed Aug. 14, 1974, Ser. No. 497,141

Term of patent 14 years

Int. Cl. D12—16

U.S. Cl. D12—157

FIG. 1

FIG. 2

FIG. 1 is a perspective view of a maintenance vehicle ladder rack showing my new design; a portion of the vehicle upon which the rack is positioned being shown in broken lines for illustrative purposes only;

FIG. 2 is a side elevational view thereof opposite to that shown in FIG. 1;

FIG. 3 is a top plan view thereof;

FIG. 4 is a front elevational view thereof;

FIG. 5 is a bottom plan view thereof; and

FIG. 6 is a rear elevational view thereof.

I claim:
The ornamental design for a maintenance vehicle ladder rack, substantially as shown.
